UNITED STATES PATENT OFFICE.

KATIE L. TRAWEEK, OF WAELDER, TEXAS.

TRUNK.

1,194,323.

Specification of Letters Patent.

Patented Aug. 8, 1916.

Application filed October 12, 1915. Serial No. 55,412.

To all whom it may concern:

Be it known that I, (Mrs.) KATIE L. TRAWEEK, a citizen of the United States, residing at Waelder, in the county of Gonzales 5 and State of Texas, have invented a certain new and useful Improvement in Trunks, of which the following is a specification.

My invention is an improvement in traveling trunks, and consists of the construction, combination and arrangement of parts 10 herein described and claimed.

The principal object of my invention is to provide a trunk in which all the conveniences of home are embodied. The trunk is 15 especially adapted to the use of tourists when remaining abroad for a great length of time, and for purposes of convenience at such times, the trunk embodies a wardrobe, an arrangement of drawers, suitable trays, 20 dressing case, book case and writing desk.

Another object lies in the provision of a permutation lock guard for the body of the trunk. The purpose of this latter provision is to frustrate surreptitious attempts to open 25 that part of the trunk containing the more valuable articles.

With other objects in view which shall hereinafter appear, reference is now directed to the accompanying drawings, in which:—

30 Figure 1 is a perspective view of the trunk. Fig. 2 is a section on line 2—2 on Fig. 1. Fig. 3 is a view similar to Fig. 2, showing the panels of the permutation lock guard, shifted. Fig. 4 is a section on line 35 4—4 on Fig. 2. Fig. 5 is a cross section on line 5—5 on Fig. 3. Fig. 6 is an elevation of the keyhole guard door, parts being shown in section. Fig. 7 is a perspective view showing the various devices of the 40 trunk, open. Fig. 8 is a cross section on line 8—8 on Fig. 7. Fig. 9 is a perspective view of one of the trays. Fig. 10 is a detail perspective view of the trunk, some of the parts being disconnected and other parts 45 being shown in section. Fig. 11 is a perspective view of one of the drawers. Fig. 12 is a longitudinal section of the roller drawer supports. Fig. 13 is a section on line 13—13 on Fig. 10. Fig. 14 is a detail 50 perspective view of one of the catches for the rear end of one of the drawers.

Reference is now directed to Fig. 10 of the drawings, in which 1 indicates the framework of the trunk. The framework

comprises the sides, back, bottom and front 55 of the trunk, the latter part having a large opening 2, through which access is had to the inside of the trunk.

The top 3 of the trunk is secured to the back of the trunk body by a hinge 4, the 60 top forming the dressing case when it is thrown open, as shown in Fig. 7. The dressing case contains all of the necessary articles for the completion of the toilet.

The writing compartment 5 is secured to 65 one side of the trunk by the hinge 6 and is provided with compartments in which writing materials may be kept. The writing compartment also includes a desk 7 which is supported by a collapsible brace 8, 70 as shown in Fig. 7. The brace 8 is of such a construction that it may be folded inwardly and so allow the desk 7 to swing downwardly. A door 9 is hinged to the compartment 5 so that, upon closing the 75 door, any loose articles within the compartment 5 are prevented from falling out.

The book case 10 is secured to the other side of the trunk by a hinge 11 so that the book case may be swung out for use as 80 shown in Fig. 7. The book case is suitably subdivided into compartments in which the books are stored. The books are protected by a door 12 which is opened and closed, at will.

85 A metallic sheath covers the entire body of the trunk as well as the exposed surfaces of the top 3, writing compartment 5 and book case 10. The sheath 13 on the body of the trunk is partly broken away as in 90 Fig. 10, to illustrate its application.

It is obvious that the construction of the trunk involves the methods in vogue, the parts being nailed and riveted in places where it is required and the frame is 95 strongly braced by any well known means.

The bottom of the trunk is braced by a longitudinal brace 14 and a central cross-brace 15 as shown in Fig. 10. A series of rectangular frames 16 are secured to the 100 trunk structure, at suitable intervals, as shown in Fig. 10. The intermediate frames 16 are paneled and form partitions between adjoining compartments in which articles of clothing may be kept. The upper 105 rails of the frames 16, are apertured at intervals as at 17, (see Fig. 12).

The frames 16 support roller bearings on

which drawers 18 are adapted to roll or bear. The roller supporting shafts comprise three elements 19, 20 and 21, the intermediate element 20 (see Fig. 12) having lateral spindles 20^a and 20^b of reduced diameters. The juncture of the spindles with the shaft 20, at either side forms a shoulder adjacent to the frames 16. A roller 22 is mounted on the spindles 20^a and 20^b between the aforesaid shoulders and frames 16. Each extreme shaft 19 and 21 is provided with a spindle 19^a and 21^a which rests in the adjacent aperture 17 in the outermost frames 16. Rollers 23 and 24 are mounted on these spindles 19^a and 21^a adjacent the frames 16 and the shoulders formed on the shafts 19 and 21 at the juncture of the spindle and shaft. The inner end of each of these shafts 19 and 21 is recessed as at 19^b and 21^b, the extended ends of the spindles 20^a and 20^b being adapted to rest in these recesses and so form one continuous shaft. Rollers 25 and 26 are mounted on the spindles 20^a and 20^b adjacent to the inner ends 25 of the extreme shafts 19 and 21 and the intermediate frames 16. This construction affords a strong and easily rolling support for the drawers 18.

The drawers 18 are of the well known construction and may be pulled out by a suitable strap handle 27. Flaps 28 may also be attached to the drawers so that when the flaps are closed the contents of the drawers may be either wholly or partially concealed. A horizontal partition 29 serves to close off the tops of the drawers 18.

The drawers 18 are prevented from falling out when fully opened, by a catch 30. A hook 31 (see Fig. 14) may be substituted 40 for a more permanent lock, for each drawer, the purpose of the hook being to prevent the drawers 18 from sliding from their places, as the trunk is conveyed.

Secured to the sides of the trunk just 45 above the partition 29 (see Figs. 8 and 10) are cleats 32 which support a lower tray 33 (see also Fig. 9). The lower tray has a number of heart-shaped boxes 34 in which valuables of different kinds are kept. The 50 boxes have suitable lids as shown.

An upper tray 35 rests on the tray 33. The tray 35 is provided with a central glass covered box 36 which may be used as a hat box or for other delicate articles while each 55 end of the tray is provided with an open compartment 37 in which other hats may be placed. The remainder of the tray 35 being of a good dimension permits it to be used for such purposes as a packing place for 60 articles of immediate use or as a work box in which sewing accessories may be kept.

For purposes of transportation the trunk is provided with stout handles 38 and 39 on its front and rear sides.

65 Mounted on each corner of the body of

the trunk is a caster 40, while similar casters are also mounted on the writing compartment and the book case. The roller of each 70 caster 40 is swivelly mounted on a bolt 41 which in turn is secured to a bracket 42, the bracket 42 being secured to the bottom of the trunk.

The opening 2 in the front of the trunk is closed by doors 43 and 44, these doors being mounted on suitable hinges 45 at each 75 side. The upper and lower edges of the opening 2 are provided on the inside with jam strips 46 against which the doors close. The door 44 also has a jam strip 47 (see Fig. 7), against which the opposing door 80 43 abuts when both doors are closed.

The doors, when closed, are interlocked by an arrangement of corresponding notches and projections 48 and 49 which fit together very closely. It will be also observed that 85 where abutting edges occur into which moisture and dirt might enter, facing strips 50 have been provided, these strips serving to make tight joints.

A lock 51 secures the doors 43 and 44, 90 when they are closed. The lock is protected against undesired tampering, by a permutation guard 52 which consists of a series of rectangular frames 53, four being shown in the drawing. The two inner frames are 95 provided with rectangular openings which are grooved as at 54 and 55 in their top and bottom surfaces.

Slides 56 and 57 which may be moved 100 back and forth are mounted in these respective grooves. The slides 56 and 57 have openings 58 and 59 which are out of registration when the slides are positioned as in Fig. 2, but when the slides are moved to the position shown in Fig. 3, the openings 58 105 and 59 are in alinement and a passageway is provided for the key 60 to the lock 51. Each slide is roughened as at 61 so that the fingers can readily manipulate the slides. Hooks 62 are provided for the retraction of 110 the slide on which it is mounted when the slide is back and in the position shown in Fig. 3, the hooks enable the operator to pull the slide out, previous to closing the outer door 63. The door 63 fits very tightly in 115 the opening in the outer one of the frames 53. The door 63 is held in place by a spring 64 which is engaged at one place (see Fig. 6) by the shank 65 of a button which has a head visible adjacent to the door 63 (see 120 Fig. 1). When the button is pushed, then the spring 64 is moved from the door 63 which may then be opened.

Upon shifting the slides 56 and 57 until a 125 passageway is established through the opening in the rearmost one of the frames 53, a key 60 may then be inserted and the lock opened.

The top 3, the book case 10 and the writing desk 5 are provided with suitable locks 66, 130

while straps 67 serve as a convenient means for opening and closing the different compartments.

From the foregoing the construction of the device may be readily understood, but it is obvious that various modifications may be made without departing from the spirit of the invention or the scope of the claims.

I claim:—

- 10 1. In a trunk, the combination with a frame having an open front, closed ends and superimposed movable compartments therein, a lid for closing the frame top and preventing access to said compartments, locking means for said lid, laterally disposed swingable compartments at the ends of the frame and closing thereagainst and against said lid, and locking means for said last named compartments.
- 15 2. In a trunk, the combination with a frame having closed ends, of laterally movable drawers, means for supporting the drawers, superimposed trays arranged above the drawers, a lid hinged to the frame and adapted to close over the upper one of the said trays, locking means for the lid, individual compartments hinged to the ends of the body of the trunk and closing against said ends and said lid, and locking means 25 for said last named compartments.
- 20 3. In a trunk, the combination with a trunk body having an open front and top, a lid for closing the top of the body, locking means therefor, doors for the open front, locking means for said doors, compartments hinged to the ends of the trunk body and closing thereagainst and against said lid, said compartments being each of a like cross 35 sectional contour to the cross sectional contour of the trunk body, locking means for 40

the said compartments, and means overlapping the closure joints of the tops, doors, and compartments.

4. In a trunk, the combination with a trunk body having an open front and top 45 and closed at the ends thereof, a lid for closing the top, doors for closing the open front, compartments hinged to the said closed ends of the body, said compartments being each of a like cross sectional contour 50 to the cross sectional contour of the trunk body and its lid and closing thereagainst, and means overlapping the closure joints of the said lid, doors, and end compartments.

5. A trunk comprising a rectangular body 55 having an open front, a top, a series of superposed drawers arranged lengthwise of the body and slid able through the open front thereof, trays arranged above the drawers and movable through the top of the body, side compartments hinged to the ends of the body and projecting above the top thereof, and a lid closing the top of the trunk body and the inner sides of the projecting portions of the side compartments. 60 65

6. A trunk comprising a body having an open top, compartments hinged to the sides of the trunk and adapted to close against the same, said compartments having their upper portions projecting a short distance 70 above the top of the trunk body, and a lid for closing the top of the trunk body and movable between the projecting portions of the side compartments hinged to the trunk body to close the latter.

MRS. KATIE L. TRAEEK.
